UNITED STATES PATENT OFFICE.

JOHN C. SCHENK, OF DETROIT, MICHIGAN, ASSIGNOR TO PENINSULAR STOVE COMPANY, OF DETROIT, MICHIGAN, A CORPORATION OF MICHIGAN.

GAS-STOVE CONSTRUCTION.

Application filed March 7, 1927. Serial No. 173,496.

This invention relates generally to gas ranges and consists of certain novel features of construction, combinations and arrangements of parts as will be hereinafter more 5 fully described and particularly pointed out in the appended claims.

Heretofore the mixing tubes or manifolds of gas ranges have been supplied with gas and air at the front of such ranges. Usually the forward ends of such manifolds have been provided with closures which had openings for receiving air from the atmosphere and had other openings that received lateral extensions of horizontally disposed gas conduits located in front of the ranges. Ordinarily such conduits were supported by hangers that projected outwardly from the front walls of the ranges. With such constructions, the valves for the air were at 20 the forward ends of the manifolds and the valves for controlling the supply of gas to the manifolds were mounted on the lateral extensions of the main supply conduit. As a result air drafts often times caused the 25 flames of the discharge ends of the manifolds to be extinguished, and frequently clothing and other articles caught on the gas valves and caused such valves to be accidentally and improperly actuated.

With the present invention the gas manifolds extend through the rear walls of the ranges and receive their supply of air and gas at the rear of such ranges. With this construction, the air and gas control valves are also located at the rear of the ranges but are adapted to be conveniently operated from the front of the ranges. Hence air drafts cannot effect the supply of air to the manifolds, and the gas valves cannot accidentally be actuated or tampered with. Moreover my construction eliminates the 40 hangars heretofore necessary to support the gas supply conduits. In fact gas ranges constructed as described herein are neater in 45 appearance and are more readily kept clean.

In the accompanying drawings:

Figure 1 is a front elevation of a gas range embodying my invention.

Figure 2 is a top plan view thereof showing parts broken away.

Figure 3 is a vertical sectional view taken on the line 3—3 of Figure 2.

Figure 4 is a fragmentary vertical sectional view taken on the line 4—4 of Figure 2.

Figure 5 is a detail sectional view of a portion of one of the manifolds.

Referring now to the drawings, 1 is the front wall, 2 is the rear wall, and 3 is the open top of a gas range embodying my invention. As shown the mixing tubes or manifolds 4 are located as usual immediately below the open top 3 but in the present instance preferably extend through the rear wall 2 and receive the upper ends of branch pipes 5 leading from the horizontally disposed main gas supply pipe 6. As usual the open ends of the manifolds are provided with closures 7 that in turn have openings 8 that receive the branch pipes 5, and have 70 openings 9 for receiving air from the atmosphere. Suitable rotary valves 10 are mounted on the rear ends of these manifolds for controlling the supply of air through the openings 9 to the manifolds, while suitable 75 rotary valves 11 are located in the branch pipes 5 for controlling the supply of gas from the main conduit 6 to the manifolds. As shown the air valves 10 are adapted to be adjusted by hand in the usual way, but the 80 gas valves 11 are preferably operated from the front of the range by rod 13 that are journalled in the front and rear walls 1 and 2 and are terminally secured to said valves 11. Any suitable means such as the handles 14 may be secured to the forward ends 85 of these rods for actuating the same.

With this construction a conventional form of gas lighter 15 is also supplied with gas at the rear of the range. As shown a branch pipe 16 leads from the main gas supply pipe 6 through the rear wall 2 and is terminally connected to the lighter 15 which in turn is located below the open top 3 preferably at a point approximately midway between the inner manifolds 4. A valve 17 is located in this branch pipe 16 to control the supply of gas from the pipe 6 to the lighter and is adapted to be operated from the front of the range by a rod 18. As shown this rod 18 is slidably mounted in the front and rear walls 1 and 2 of the range and has an offset portion 19 engageable with the lower end of the valve stem or plunger 20 for actuating the same. If desired a bracket 21 may be secured to the inner face of the rear wall 2 to serve as an auxiliary bearing for the rod 18. Any suitable means such as a handle 22 may be secured to the forward end of the rod 18 to actuate the same.

In use, the valves 11 and 17 at the rear of the range may be readily operated by rotating the proper handles 14 and 22 at the front of the range.

5 While it is believed that from the foregoing description, the nature and advantage of my invention will be readily apparent, I desire to have it understood that I do not limit myself to what is herein shown and 10 described and that such changes may be resorted to when desired as fall within the scope of what is claimed.

What I claim as my invention is:

1. In a gas range, the combination with 15 the front and rear walls thereof, of a substantially horizontally disposed gas supply pipe located in rear of said rear wall, a branch conduit leading from said main supply conduit through the rear wall aforesaid 20 terminating at a point between said front and rear walls, a valve in said branch conduit, and means for controlling said valve including a member supported by and extending through both said front and rear 25 walls.

2. In a gas range, the combination with the front and rear walls thereof, and an open top upon said front and rear walls, of 30 gas manifolds located below said open top 35 and extending through said rear wall, a main gas conduit in rear of said rear wall, branch conduits extending between said gas manifolds and main conduit and supporting the latter from the former, valves controlling the flow of gas from said main conduit to said manifolds, said valves being in rear of the rear wall aforesaid of said range, and actuating means for said valves including independently operable means extending 40 through said front and rear walls and operable from a point in advance of the front wall of said range.

3. In a gas range, the combination with the front and rear walls thereof, and an open top upon said front and rear walls, of gas manifolds located below said open top and 45 extending through said rear wall, a main gas conduit in rear of said rear wall communicating with said manifolds, valves controlling the flow of gas from said main conduit to said manifolds, said valves being in rear of the rear wall aforesaid of said range, and a plurality of horizontally aligned valve actuating rods supported by 50 and extending through said front and rear walls and operable from a point in advance of said front wall.

4. In a gas range, the combination with the front and rear walls thereof, of a substantially horizontally disposed gas supply pipe located in rear of said rear wall, a branch conduit leading from said main supply conduit through the rear wall aforesaid terminating at a point between said front and rear walls, a valve in said branch conduit including a reciprocating plunger, and means for controlling said valve including a rod extending through both said front and rear walls and engaging said plunger.

5. In a gas range, the combination with 70 the front and rear walls thereof, of a substantially horizontally disposed gas supply pipe located in rear of said rear wall, a branch conduit leading from said main supply conduit through the rear wall aforesaid 75 terminating at a point between said front and rear walls, a valve in said branch conduit including a reciprocating plunger, and a rod slidably mounted in said front and rear walls engaging said plunger, and 80 adapted to actuate the same upon movement of said rod.

In testimony whereof I affix my signature.
JOHN C. SCHENK.
